(57) **CLAIM**

The ornamental design for marine slam latch, as shown and described.

DESCRIPTION

FIG. 1 is a top plan view of a marine slam latch housing showing our new design;

FIG. 2 is bottom plan view thereof;

FIG. 3 is a front elevational view thereof, the rear elevational view being a mirror image thereof;

FIG. 4 is a right side elevational view thereof, the left side elevational view being a mirror image thereof;

FIG. 5 is a top rear perspective view thereof; and,

FIG. 6 is a top front perspective view thereof.

The broken lines are for illustrative purpose only and form no part of the claimed design.
